UNITED STATES PATENT OFFICE.

CHESTER W. CANINE, OF NORWOOD, OHIO, ASSIGNOR TO THE NATIONAL MARKING MACHINE COMPANY, OF CINCINNATI, OHIO, A CORPORATION OF OHIO.

INKING MECHANISM FOR MARKING-MACHINES.

1,079,592.

Specification of Letters Patent. Patented Nov. 25, 1913.

Application filed May 20, 1912. Serial No. 698,471.

To all whom it may concern:

Be it known that I, CHESTER W. CANINE, a citizen of the United States, residing at Norwood, in the county of Hamilton and 5 State of Ohio, have invented certain new and useful Improvements in Inking Mechanism for Marking-Machines, of which the following is a specification.

My invention relates to an improvement 10 in inking mechanism for marking or numbering machines and primarily adapted to be used with a type of printing device, having its printing and type setting elements and the control therefor mounted upon a 15 swinging head, with the printing characters movable to and from a stationary printing platen. The drawings illustrate such type of marking machine as may be termed a self-contained marking and type setting swinging head operated by power means. It is 20 evident, however, that my invention may be embodied in other types of numbering or marking machines.

An object of my invention is to provide 25 inking mechanism for a marking machine having an ink reservoir and ink distributing pad thereof movable to and from the type characters to be inked and engage the type characters in a parallel plane with the face 30 of the type, as contradistinguished from a rubbing or wiping action with the ink reservoir and its ink distributing surface movable relatively with the type characters in their movement to and from the printing 35 platen.

Another object of my invention is to provide an ink distributing pad movable relatively to type character set to printing position with the ink distributing pad arranged 40 to automatically engage the printing surface of the type characters toward or at the limit of receding movement after each impression with the ink distributing pad advancing into the path of the type characters 45 in an aligned plane with the type character surfaces.

Another object of my invention is to provide inking mechanism for marking or machines of like character, movably mounted, 50 with its ink distributing surface normally free from type contact, and in connection with treadle operated means, whereby the ink distributing surface is brought into engagement with the type in advance of the

movement of the type and with the controlling mechanism serving to guide or direct and advance the inking mechanism so as to engage and ink the type automatically, during, toward or at the limit of receding movement of the impression surface after each 55 impression.

Another object of my invention is to provide ink distributing mechanism for marking machines comprising primarily an ink reservoir having an ink distributing pad 60 with lever mechanism mounted upon and movable with the frame of the numbering machine, and lever mechanism separate and independent of the said frame for controlling and directing the movements of the ink- 65 ing mechanism.

The features of my invention are more fully set forth in the description of the accompanying drawings, forming a part of this specification, in which:—

Figure 1 is a side elevation of a numbering machine of a particular type, having a swing frame, having type disks and setting mechanism therefor mounted upon and movable with the swing frame, with my 80 improvement applied. Fig. 2 is an enlarged detail side elevation of the inking mechanism forming the subject-matter of this invention and illustrating a portion of the marking machine frame and type disks with 85 the parts in the same position as illustrated in Fig. 1. Fig. 3 is a section on line x, x, Fig. 2.

The type of marking machine illustrated is substantially of a type as illustrated in a 90 prior application filed by me on June 21, 1909, Serial No. 503,404, and only so much of the numbering machine is herein illustrated as to convey and disclose the general 95 character and style of the machine, showing the application of my invention to such machine. It is obvious, however, that my invention is applicable to other types of machines either manual or power driven.

The general organization of the machine 100 shown comprises a pedestal 1, upon which is supported the main frame 2. The frame 2 is provided with upwardly projecting brackets 3, in the view of the drawings only one is seen, and preferably formed integral with 105 the frame. Between these brackets 3 the side frames 4 are pivotally mounted, forming a housing and support for the type disks and

mechanism for operating the type disks to set a given character of each disk to its printing position and restore the same to normal for a second setting.

- 5 represents one of a series of type disks formed in the nature of gears with the indicating characters upon the periphery of the teeth. These type disks are loosely journaled upon a spindle 6 mounted within the 70
 10 swinging side frames 4. The type disks of the series are all the duplicates of each other, with the characters of the disks symmetrically arranged to provide longitudinal alinement of duplicate characters of the disks 75
 15 of the series in a normal position, with an acquisition necessitating only one set of keys, equal in number to the number of characters upon a single type disk, to control or accomplish the setting of respective characters of 80
 20 each of the disks of the series to a printing position. The mechanism for rotating the type disks or setting a given character or characters thereof to printing position or to restore the same to normal may be substantially 85
 25 the same as that shown and described in my aforesaid prior application, or any other means may be employed for accomplishing the same result. It is preferable, however, to have the type disks formed as 90
 30 a gear with an element of the setting mechanism intermeshing between the teeth for rotating the disks, as it provides compactness and economy over other forms, all of which, however, does not concern or affect 95
 35 the features of this invention. The machine illustrated is designed to be operated by power.

- 7 represents an electric motor supported upon the pedestal 1.
 40 8 represents a belt connected with motor pulley 9 and with a pulley 10. The pulley 10 is connected with transmission mechanism comprising a system of gear and clutch mechanism for imparting motion to a gear 11.
 45 12 represents a pitman connected to the gear 11 and the swing frame 4, whereby the frame is rocked upon each rotation of the gear 11.

In marking articles, such as wearing apparel for identification, in laundries, it has been found most desirable to use ink in liquid form fed to a pad for inking the type characters, as a higher quality of printing and permanency of print can be obtained. 50
 55 Therefore, it is essential to properly present the ink distributing pad to the type and this can be most successfully accomplished in presenting the pad in a plane substantially parallel with the face of the type and uniformly pressed over the entire surface of characters in contra-distinction from a rubbing action across the face of the type characters. 60

With my invention, the ink distributing pad is presented to the type surface and

withdrawn therefrom in the most efficient manner, to attain the best results. The ink can be uniformly distributed to each type character in printing position, without distributing ink to adjacent characters not in printing position and a promiscuous throwing of ink prevented, which latter tendency is practically inherent in rapid power driven machines. Therefore, the efficiency of the inking mechanism is of vital importance in this class of machines. The marks of identification for laundry articles must be clear, distinct and permanent to avoid confusion or hamper the speed in assorting.

13 represents an ink reservoir having a pad 14 in communication with the ink supply within the reservoir and the feed thereto preferably controlled by valve mechanism, not illustrated.

15 represents a link pivotally connected to one end of the reservoir with the opposite end of the link pivotally connected to the side frame 4.

16 represents a link pivotally connected to the ink reservoir and to a lever 17 with the lever 17 pivotally connected to an extension 18, of the bracket 3. The link 15 is also pivotally connected to the lever 17, by a pin 19, projected from the lever and engaging through an elongated slot 20 in the link 15. The opposite end of the reservoir is provided with a set of links and lever, the duplicate of links 15, 16, and lever 17, and connected in substantially the same manner.

21 represents a yoke bar, vertically supported with its limbs 22, each adapted to engage a respective lever 17. Each limb 22 is slidably mounted upon its respective adjacent bracket extension 18, by means of a pin 23 engaged with the bracket extension and passing through an enlarged slot in the limb 22, (see Fig. 2). The yoke bar 21 is connected to a lever arm 24 fixed to a shaft 25 suitably journaled and supported in bearings on the base plate 2. The shaft 25 serves to actuate the clutch mechanism controlling the transmission.

26 represents an actuating rod connected to the arm 24 and to the treadle 27, see Fig. 1.

Mode of operation: By applying pressure upon the treadle 27, the actuating rod 26 and yoke bar 21 will be moved vertically, which will also rock shaft 25 throwing in the power for rocking the frame 4, and actuate the levers 17, moving the links 16 downward, swinging the ink reservoir upon the links 15 to bring the pad 14 into engagement with the type disks 5. This initial inking action is accomplished simultaneously with the starting of the machine and the machine continues in operation as long as the treadle remains depressed. With the controlling mechanism in operative position the ink pad will always be brought into contact with the type characters in the normal- 125 130

izing movement of the swinging head. The printing stroke of the swinging head diverts the fulcrum of the ink reservoir from the links 16 to the links 17 resulting in swinging the ink pad away from the type characters sufficiently to offer clearance for the printing platen. The movement for platen clearance is accomplished when the links 16 engage with the pins 19 of the lever 17, to swing the inking mechanism as a unit with the head. In such instance the free ends of the levers 17 disengage from the limbs of the yoke bar 21, and upon the return movement reengage therewith to arrest their movement. Two sets of links 15, 16 and levers 17 are provided for equalization, in supporting the inking reservoir, although their use in the singular is comprehended herein, and the levers 17 may be integrally connected to comprise a single unit.

It is apparent from the mechanism herein shown and described that the meeting surfaces of the type characters and inking pad approximately relatively engage each other in a diametric line with the fulcrum axis of the reservoir, when the fulcrum is upon the link 16, thereby presenting the pad in a longitudinal plane substantially parallel with the face of the type characters. The ink reservoir moving in the direction as described the pad in one instance is maintained above the ink level within the reservoir, that of the type inking position, and below the level for replenishing the pad, the ink flowing to the pad by gravity and its quantity regulated by a valve interposed between the pad and supply. The operation of the machine is such that the swinging head will always move to its limit of upward movement upon release of the treadle before the machine is brought to rest, thereby insuring the release of the pad from any type engagement, permitting free manipulation of the type disks for resetting.

Having described my invention, I claim:—

1. In a marking machine, a numbering head, providing a swinging frame and type disks journaled thereon, an ink reservoir pivotally connected to the frame beneath the surface of the type to be inked, a lever mounted separately from the frame, and pivotally connected to the ink reservoir and movable with the swinging frame, means for arresting the movement of the said lever to thereby actuate the ink reservoir independent of frame movement to engage the reservoir with the type.

2. In a marking machine, having type disks mounted upon a frame movable to and from a printing platen, in combination with an ink reservoir having an ink distributing surface movable with the frame to and from the printing platen and independent thereof to and from the type, link and lever mechanism connecting the ink reservoir to the

frame and independent of the frame, treadle mechanism controlling the motive power for the frame and actuating said lever mechanism, whereby the ink distributing surface of said reservoir is normally free from type contact and brought into engagement therewith simultaneous with the initial movement of the swinging frame.

3. In a marking machine, the combination with a swinging type carrying frame, of an ink reservoir pivoted to the frame and moving therewith, a member separate from the frame pivoted to the ink reservoir and moving with the frame in one direction and arrested toward the limit of movement of frame in an opposite direction, to swing the ink reservoir independently of the frame movement and against the type to ink the same.

4. A device of the nature disclosed combining a series of type characters in longitudinal alinement and support therefor, inking mechanism for said type characters comprising a lever member mounted upon a fixed fulcrum, an inking pad supporting member, a link hingedly connecting said pad supporting member to the type character support, and a link hingedly connecting said pad supporting member to said lever member, whereby the fulcrum of said pad supporting member is alternately diverted to move the pad supporting member from a normal position toward and from the type characters and from the normal position to a position more remote from the type characters in each printing operation.

5. A device of the nature disclosed combining a series of type characters in longitudinal alinement, a swingingly mounted inking pad holder support, an inking pad holder and inking pad therefor fulcrumed on said support with its axis approximately in a diametric plane with the engaging plane of said type characters and inking pad, and lever mechanism engaged with said holder for maintaining said pad in type engagement during non-printing intervals.

6. A device of the nature disclosed combining type characters in printing position and support therefor, an inking pad, a member fulcrumed relatively to the type characters for supporting said pad, having its axis approximately in a diametric plane with the meeting plane of said type characters and pad, and lever mechanism for swinging said member and maintaining said pad in engagement with the type characters during non-printing intervals.

7. A device of the nature disclosed combining a swinging type carrier frame, type characters in longitudinal alinement thereon, a lever member pivotally mounted independent of said frame, an inking pad supporting member and pad therefor, a link pivotally connected to said frame, lever

member and inking pad supporting member, a second link pivotally connected to said lever member and pad supporting member, whereby said member may be normally operated to bring the pad into engagement with the type characters and swing with said type carrier frame to move the pad away from said type characters.

8. A device of the nature disclosed combining a swinging type carrier frame, an inking pad holding member pivoted to the frame movable therewith, and having its fulcrum approximately in a diametric plane with the surface of the type upon said carrier frame, an inking pad mounted on said holder, a member pivotally independent of the frame and pivotally connected to inking pad holder for rocking the holder to move its pad to and from the type, and power controller mechanism for said carrier frame adapted to bring said inking mechanism into its qualifying position.

9. A device of the nature disclosed combining a swinging type carrier frame, an inking pad supporting member pivoted to the frame capable of moving therewith, a pivoted member independent of the frame pivotally connected to said inking pad holder, whereby in an independent movement of said pivoted member the inking pad holder can be rocked upon its carrier frame fulcrum to bring the holder into engagement with the type with its fulcrum diverted to said pivoted member to position said holder away from the type in the printing stroke of said carrier frame.

In testimony whereof, I have hereunto set my hand.

CHESTER W. CANINE.
